BRIDLE BIT

Filed May 10 1927

Patented Feb. 28, 1928.

1,660,490

UNITED STATES PATENT OFFICE.

WILLIAM L. KOCH, OF TRELOAR, MISSOURI.

BRIDLE BIT.

Application filed May 10, 1927. Serial No. 190,208.

The invention relates to bridle bits and has for its object the provision of means connecting the bit bar with the cheek ring to which the cheek straps of the bridle are secured by which the bit may be reversed without removing the bridle from the head of the animal, so that a smooth side or bit bar may be arranged to engage the jaws of the animal or toothed side of the bit may be 5 presented toward the jaws, the construction admitting of changing the nature of the bit without removing the bridle from the head of the animal and without removing the bit from the bridle.

10 A further object of the invention is the provision of a bridle bit having cheek rings provided with parallel transverse bars and providing the bit bar with pivotally engaged headed studs on its ends slidably engaging 15 between the parallel bars in the cheek ring, the bars on one of the cheek rings having their upper ends spread to permit rotation of the bit bar to reverse the bit bar, said adjustment being adapted to be effected 20 while the bridle is in position on the animal's head.

25 The invention will be described in detail hereinafter and will be found illustrated in the accompanying drawings, in which

30 Figure 1 is a view in elevation of one side of the improved bridle bit.

35 Figure 2 is a similar view of the opposite side,

40 Figures 4 and 5 are sectional details on planes indicated by the line 4—4, and 5—5 of Figure 3.

45 In the drawings similar reference characters will be used to designate corresponding parts throughout the several views.

50 The improved bridle bit comprises the cheek rings 1 and 2 to which are secured the cheek straps of the bridle as shown in Figures 1 and 2. The cheek ring 1 is provided with transverse bars 3 that are arranged parallel to one another throughout their length, while the cheek ring 2 is provided with bars 4 having their upper ends spread 55 to form an enlarged recess as shown at 5, and the remainder of the bars are formed parallel. The bit bar 6 has one of its sides smooth as shown at 7 to provide an easy

bit, while the opposite side of the bit is provided with a series of blunt teeth 8 that 55 provide a severe bit for fractious animals. The ends of the bit are provided with reduced extensions 9 and pivotally engaging said reduced extensions 9 at one end of the bit bar 6 is a round stud 10 having a head 60 11 thereon, said round stud slidably engaging between the parallel bars 3. Pivotally engaging the reduced extensions 9 at the other extremity of the bit bar 6 is a stud 65 12 that is rectangular in cross section and provided with a head 13. The stud 12 slidably engages between the bars 4 and held from rotation when between the parallel portions of said bars, but is adapted to be rotated and to rotate therewith the bit bar 70 when the stud 12 is moved into the recess 5 formed by the upper spread portions of the bars 4, this rotation of the stud and with the bit providing means by which the nature of the bit may be changed from an easy bit 75 using the smooth side 7 to engage the animal's jaws, to a severe bit in which the toothed side 8 engages the jaws of the animal. Also the construction admits changing the nature of the bit while the bridle is on 80 the animal's head it being apparent that the only thing necessary to do being to lift the bit bar 6 until the stud 12 may be rotated within the recess as hereinbefore stated.

What is claimed is:—

1. A bridle bit comprising cheek members, said members having elongated slots, a bit bar slidably mounted in said slots and normally held against rotation, one of said slots having an enlargement to permit rotation 90 of the bar to reverse the same, said bit having dissimilar edges adapted to be brought into contact with the mouth of the animal through said reversal.

2. A bridle bit, comprising cheek rings, 95 pairs of parallel bars arranged transversely of the rings, the pair of bars in one ring being spread at one point, a bit bar having ends slidably mounted between said bars, the end mounted between the last mentioned pair of bars being non-rotatable between the parallel portions thereof and movable into the spread portion to permit rotation of the bit bar.

In testimony whereof I affix my signature.

WILLIAM L. KOCH.
